UNITED STATES PATENT OFFICE.

ENOCH A. MAYOR, OF SAN ANTONIO, TEXAS.

PIANO-ACTION.

1,135,386.

Specification of Letters Patent. Patented Apr. 13, 1915.

Application filed October 7, 1912. Serial No. 724,414.

To all whom it may concern:

Be it known that I, ENOCH A. MAYOR, citizen of the United States, residing at San Antonio, in the county of Bexar and State of Texas, have invented certain new and useful Improvements in Piano-Actions, of which the following is a specification.

My invention relates to piano actions and particularly to that part of the action which 10 controls the rebound of the hammer and includes the back stop, the back check, bridle strap and the supporting members therefor.

The primary object of my invention is to simplify this part of the piano, reduce 15 the number of parts involved therein and increase the valuable space within the piano case so that other mechanisms may be placed within this space and not incommode the action itself, thus adapting the device particularly to player pianos.

A further object is to eliminate the bridle strap and the supporting wire therefor. This strap is frequently injured or destroyed 25 by mice and then the hammer fails to work properly, especially when the instrument is exposed to dampness. By eliminating the bridle strap and providing a positive means for retracting the hammer, the action is made more certain, the cost of manufacture 30 reduced and the chance of injury above referred to is entirely eliminated.

A further object of the invention is to provide a catcher or hook mounted upon the back check and engaging the back stop 35 so that as the wippen falls upon the release of a key, and if the hammer sticks, the hook will engage the back stop and retract the hammer as is illustrated in my pending application, Serial No. 648,231, filed September 7, 1911.

A further object is to so form this catcher hook that it is readily adjustable by bending so as to increase or decrease the distance between the bill of the hook and the face 45 of the back check.

A further object is to so form this hook that it may be readily adjusted longitudinally of the back check either by rotating the back check and holding the hook steady 50 or by rotating the hook itself.

A further object is to so attach the hook to the back check as to prevent all chance of "rattle."

Still another object is to provide means

for preventing the wippen from falling 55 down when the action is being handled and taken out of the piano case.

Other objects will appear in the course of the following description.

My invention is illustrated in the accompanying drawings wherein:

Figure 1 is a sectional view of a portion of an upright piano action, the hammer being in its normal or retracted position. Fig. 2 is a like view to Fig. 1 but showing the 65 position of the parts occupied by them after the hammer is struck and before it is retracted. Fig. 3 is a fragmentary side elevation of the back check and the hook mounted thereon before the hook is bent downward 70 into its back stop engaging position. Fig. 4 is a fragmentary section of the back check, the dotted lines showing the different ways in which the hook may be bent in order to adjust it. Fig. 5 is a view like Fig. 4 but 75 showing another manner of bending the hook to secure a proper adjustment thereof.

Corresponding and like parts are referred to in the following description and indicated in all the views of the accompanying drawings by the same reference characters.

Referring to these drawings, 2 designates the action rail and 3 the wippen pivotally mounted upon the action rail by means of the wippen flange 4.

5 designates the hammer-butt pivotally mounted upon the action rail by means of the flange 6, and 7 designates the jack or fly which is pivotally carried upon the wippen 3 by means of the flange 8.

9 designates the knock-off or regulating button disposed upon the regulating rail 10.

The hammer 5 carries the hammer shank 11 which at its end supports the hammer 12. This hammer normally bears 95 against the hammer rest rail 13. These parts are those ordinarily to be found in upright piano actions and require no further description.

Projecting from the front face of the butt 100 5, that is, the face opposite the strings of the instrument, is a shank 14 carrying upon its end the back stop 15. This back stop is somewhat longer than the back stop ordinarily found in standard piano actions, that 105 is, it is extended upward as at 15^a, the outer face of the extension 15^a being disposed inward from the face of the body of the stop

while the inner face is beveled. This back stop on its front and rear faces is, of course, to be covered with leather 16 as is usual.

Supported upon the wippen 3 is the upwardly projecting back check wire 17 carrying at its upper end the ordinary back check 18 whose inner face is faced with felt 19. It will be observed from Figs. 1 and 2 that the felt 16 where it passes over upon the beveled face of the extension 15^a is not attached entirely to the beveled face but is transversely puffed as at 20 so that a space is left between the leather and the beveled face so as to render this leather somewhat elastic and cause it to form a cushion between the bill of the hook and the beveled face of the stop, thus preventing any rattle or jar when the bill of the hook engages the stop. It will be understood, of course, that the space between the leather and the stop is relatively slight.

Supported upon the upper end of the back check 18 and extending inward toward the hammer shank 11 and above the upper end 25 of the stop 15 is the hook-shaped member 21. Preferably this member is of wire or like material and is not resilient. Preferably this member is angular in form and originally has the form illustrated in Fig. 3, 30 that is, it has a shank 22 with the body portion of the hook 23 disposed at an obtuse angle to the shank and a bill 24 disposed at approximately a right angle to the shank, this bill however being slightly curved outward and being slightly flattened with the extremity bent outward as at 25. The shank 22 is screw threaded as at 26 so as to enter the wood of the back check 18.

The object in making the hook 21 angular in form is to provide for a proper bending of the hook to adjust it to circumstances. Originally as stated, the hook is inserted in the back check as shown in Fig. 3 and afterwards the workman who is adjusting the action bends the hook so as to accommodate it to the stroke of the key. It will be obvious that if the key has a relatively long or deep stroke, the hammer and consequently the back stop will move further than when the key has a shallow stroke, and that hence the hook 21 must be bent so as to bring the bill 24 nearer to or further from the inner face of the back check felt 19. This adjustment is secured by bending the hook in the manner shown in Figs. 4 and 5.

Originally the hook is as shown in dotted lines at *a* of Fig. 4. The shank may be bent inward at the junction of the body 23 with the shank 22 as shown in dotted lines at *b* in Fig. 4, or the hook may be bent so that the shank and body of the hook are at right angles as shown in full lines at *c* in Fig. 4. It will thus be seen that there is considerable difference between the position shown at *c* and the position shown at *b*,

and that the bill of the hook is much nearer the face of the felt 19 at *c* than it is at *b*. In Fig. 5 I show still another way of readily bending this hook. This increases the distance between the felt and the bill of the hook, and this increase is secured by bending the shank at the point *d*. It will be understood that this bending of the hook is greatly facilitated by the fact that the hook is angular and that the finisher who is adjusting the parts to the touch of the particular instrument may readily bend the wire forming the hook at any desired point. This is an exceedingly important point of my invention. The hooks can not be turned out so as to be the same for all actions. They must be individually adjusted by the finisher to suit the varying circumstances of each particular case. Again it is to be noted that the shank 22 is screw threaded at its end as at 26 so as to have screw threaded engagement with the back check. This also is a vital point of my invention as it provides for adjusting the height of the hook relative to the back check and relative to the stop and this adjustment may be secured by rotating the back check upon the wire 17 and holding the hook 21 from rotation. It would be impossible when the action is in place to adjust the hook 21 by rotating the hook itself inasmuch as the laterally adjacent parts of the action are too close to permit a rotation of the hook. Furthermore in finishing and regulating all upright actions, the back checks are individually raised or lowered by turning them upon the wire 17. By inserting the hook 21 in a socket formed in the back check, it is easy to rotate the back check without rotating the hook. The hook 21 should be so adjusted that when the hammer is forced against the strings as in Fig. 2, the extremity of the bill of the hook will just escape the shank 14 and the extremity of the stop will just escape touching the hook. The distance between the bill of the hook and the shank 14 should be greater than the distance between the upper extremity of the stop and the body of the hook.

In order to prevent the wippen from falling when the action is being handled and taken out of the piano case, I provide the action rail 2 with a projecting ledge 27 which as illustrated is triangular in form, the outer corner of the triangle being covered with felt 28, and the jack 7 is formed on its inner face, that is, the face towards the action rail with a shoulder 29 facing downward and adapted to rest upon the upper face of the ledge 27 when the jack has been dropped below the position shown in Fig. 2. It will be seen that this shoulder has one of the functions of the bridle tape in that it prevents the dropping of the wippen when the action is taken out of a piano

case. It will further be noted that this shoulder or ledge 27 acts to support the wippen in such position that the catcher hook 23 can not fall below the back stop 15, even should the wippen tend to drop below its normal position for any reason. In other words, the ledge 27 acts to hold the hook at all times in proper position with relation to the back check.

10 The reason for cutting away the face of the back stop 15 so as to form the shoulder 16 is that this shoulder acts to check any upward movement of the back stop relative to the back check, and I find by experience that 15 this cutting away of the outer face of the back stop lessens any sliding movement of the two parts relative to each other so that the stop will stay where checked.

Normally or when the parts are in the 20 position shown in Fig. 1, the hook 21 is spaced from the upper end of the back stop 15 but in the operation of my device when the piano key is struck, the wippen is carried upward and this upward movement of the wippen carries the back check 18 in a 25 direction toward the strings of the instrument and slightly upward and of course carries the hook 21 with it, leaving the hammer free to be projected against the strings of the

30 instrument. As the wippen falls with the release of the key, the back check is carried downward and away from the hammer and the hook 21 is also carried downward and outward, that is, away from the strings and 35 will in its movement, if the hammer be retarded, engage the bevel face of the back stop 15 and positively retract the hammer, causing it to return to its position against the hammer rail 13. The contact between 40 the bill of the hook and the felt 20 of the back stop is very slight and absolutely noiseless. This contact is just sufficient to retract the hammer if the hammer sticks.

45 My device is extremely simple, is thoroughly positive in its action and is not liable to be destroyed as is the ordinary bridle strap. Furthermore, it may be applied to any action at present in use, which is of vital importance inasmuch as manufacturers will 50 not use a device which in any way materially changes the form or operation of the parts of a piano action as ordinarily used. Furthermore it will be seen that by eliminating the usual bridle wire, the length of the 55 wippen may be reduced, thus leaving more space in front of the action for the accommodation of piano player mechanism. A reduction of even one-eighth inch in the space taken up by the regular piano action 60 where a piano player mechanism is to be installed in front of the regular piano action is of big consideration. Every effort is made to reduce the size of the action where piano player mechanism is to be disposed in front 65 thereof.

Under ordinary circumstances, the hook is spaced along its whole length from the back stop 15 and only contacts with this back stop where the hammer action is sluggish, due for instance to dampness. Where the hammer 70 fails to fall back, the extremity of the hook engages the inner face of the upper end of the stop and positively draws the hammer back. This engagement is very slight and is practically without friction. With my invention there is no necessity of having a 75 spring for retracting the hammer, though of course the spring may be used. The whole weight of the wippen, back check and attached parts act to draw the hammer back in case it sticks. The hook 21 does not bear at all upon the back stop except when the hammer is sluggish and then only upon a retraction of the hammer.

It is to be particularly noted that the bill 80 of the hook 21 is flattened as to that portion which might contact with the felt on the back stop. This prevents any wear which might take place in striking the inner face 85 of the back stop, and as there is no rubbing or sliding movement, the felt on this back stop will not be torn as it would if the bill of the hook were pointed or even merely rounded.

It may be said with regard to this invention that it is designed with particular reference to making it practical, that is, providing a device which will retract the hammer, which device however will not require that any of the parts of the action be 90 changed and retaining the quality of work and effectiveness of the upright piano action in present use, and this without increasing the cost of the action but on the contrary tending to reduce the cost.

It may also be pointed out that the "finisher" in the piano factory can glue in the hammer without unscrewing or taking off the hooks 21, thus permitting the hooks to be attached to the back check by the action 100 makers and not by the piano maker, it being impracticable as the industry is constituted today for the piano makers to do this part of the work.

What I claim is:

1. In an upright piano action, the combination with a wippen, a hammer-butt, a back stop carried by the butt and a back check carried by the wippen, said back stop having a rounded upward extension, of a 115 hammer retracting hook carried on the upper end of the back check and projecting above the same, said hook being rigid and comprising an upwardly extending shank, an inwardly extending body portion and a 120 downwardly projecting bill adapted to engage behind the rounded extension of the back stop when the hammer is raised.

2. In an upright piano action, the combination with a wippen, a hammer-butt, a 125

130

back stop carried by the butt and a back check carried by the wippen, said back stop having an upward extension having a beveled inner face, of a hammer-retracting hook 5 of wire formed with a shank extending parallel with the outer face of the back check having screw threaded engagement with the back check and projecting above the same, an inwardly bent body portion at an angle 10 to the shank, and a downwardly bent bill at an angle to the body portion, said bill being flattened and outwardly curved.

3. In an upright piano action, the combination with a wippen, a hammer-butt, a shank projecting from the hammer-butt, a back stop carried on the end of the shank and a back check carried by the wippen and opposed to the stop, said back stop having an upward extension, the outer face of 20 which is offset from the outer face of the body of the stop and the inner face of which is beveled, of a hammer retracting hook comprising a screw threaded shank, a body portion inwardly projecting from the shank 25 and having an angular relation thereto, and a bill having an angular relation to the body portion, said hook extending inward toward the hammer-butt and having its bill normally lying in a plane inward of the apex 30 of the extension of the back stop, the shank of said hook being screwed into the upper end of the back check.

4. An upright piano action including in combination an action rail, having a member projecting from the face thereof, a wippen, a jack and a hammer butt, the inside face of the jack adjacent the action rail being cut away to provide a shoulder at the upper end of the cutaway portion adapted 40 to engage with said projecting member when the wippen is down.

5. An upright piano action including in

combination an action rail having a member projecting from its outer face, a wippen, a hammer butt, a jack mounted upon the wippen and engaging the hammer butt, said jack having an outwardly projecting arm at its base, and a regulating button engaging said outwardly projecting arm, the inner face of the jack being cut away to 50 provide a shoulder at the upper end of the cutaway portion adapted to engage with said projecting member when the wippen is dropped.

6. In an upright piano action, the combination with an action rail, a wippen, a hammer-butt, a jack mounted upon the wippen and engaging at its upper end with the hammer-butt, said jack having a shoulder on its inner face engaging the projecting member on the action rail, a shank projecting from the hammer-butt, a back stop carried on the end of the shank and having an upward extension projecting above the shank, and a back check carried by the wippen and opposed to the stop, of a hammer retracting hook formed of rigid wire having a screw threaded shank extending into the upper end of the back check and rotatably mounted therein, the body of the hook extending inward from the shank towards the hammer-butt and over the rounded upper end of the back stop but normally spaced therefrom, the inner end of the body of the hook being downwardly bent to form a bill 70 adapted to engage with the beveled inner face of the back stop when the hammer is in its projected position.

In testimony whereof I affix my signature in presence of two witnesses.
